ENGINE

Filed June 29, 1932

In the construction illustrated in Fig. 1 the intake gases are introduced into the piston chamber between the heads 37 and 37' the reduced shank portion 38 connecting said heads providing a chamber 42 through which the intake gases may pass. A port 43 communicates with the chamber 42 and permits the intake gas to flow into a passage 44 communicating with the cylinder intake ports 25 so that when said cylinder intake ports are opened by the sleeve ports 27 coming into registration therewith, the intake gas may flow into the engine cylinder. In the engine illustrated, the intake gas consists of air which is taken into the cylinder, compressed and the compressed air ignites the fuel injected therein by the injection nozzle 24^a. Following ignition of the fuel charge, the usual expansion stroke takes place after which the exhaust ports are opened for exhausting the cylinder of the burned gases. Preferably, the intake ports are opened a predetermined time before the exhaust ports are closed whereby to permit the air to flow into the cylinder and to scavenge the same. The exhaust gases are forced out through the exhaust passage 45 through the port 46 into the valve chamber 36 where the same is forced through the outlet 35 into passage 33, branch 32, thence out through the exhaust gas conducting passage 31.

In the engine herein illustrated the operation is reversed by reversing the intake and exhaust manifolds. This is accomplished by moving the valve C into the position as shown in Fig. 2. In this position the valve heads 37 and 37' in cooperation with the shank 38 provide a chamber 42' in communication with the intake passage 28. However, it will be noted that the chamber 42' now communicates with the passage 45 through the port 46 and the valve chamber 36 below the valve head 37' communicates with the passage 44 by means of port 43. The passage 44 now becomes the exhaust passage of the engine and the passage 45 becomes the intake passage, and cylinder ports 24 become intake ports and cylinder ports 25 become exhaust ports. The engine cyclical events are the same but the exhaust gases are exhausted through the branch 32'. The reversing of these intake and exhaust passages permits the reverse of the engine cyclical events on starting the engine in a reverse direction.

In multi-cylinder engines, chambers 44' and 45' preferably extend longitudinally of the engine to connect all the engine cylinders to the intake and exhaust gas conducting means 28 and 31. I preferably employ a common rail variable pressure fuel supply system including a rail 50, connections 51 connecting the rail to each of said injection instrumentalities 24^a, and a fuel pump 52 for supplying fuel under pressure to the rail 50 from tank or reservoir 53, said pump being operatively driven by the engine crankshaft 54 through a suitable transmission 55 as described and claimed in my co-pending application, Serial No. 479,836, filed September 5, 1930, in which the fuel atomizing device is provided with a valve that is mechanically controlled for opening and closed in response to a predetermined pressure drop.

In Figs. 3 and 4 I have illustrated a timing diagram for forward and reverse engine operation. It will be noted that the opening period of said ports is not varied with respect to crankshaft angle and also the pump delivery period is not altered. In the forward operation of the engine the sleeve valve actuating crank is advanced with respect to the crankshaft. The port

25 is opened by the piston but is closed by the sleeve port lower edge. The port 24 is both opened and closed by the sleeve port lower edge. When reversing engine operation, the intake and exhaust port means are interchanged, the pumping period and injection periods remain unchanged, and Figs. 3 and 4 diagrammatically illustrate in a crank diagram when injection begins (I. B.), injection ends (I. E.), and when the pump delivery begins (P. B.) and when pump delivery ends (P. E.). In the forward operation of the engine the pump delivery period takes place just prior to the injection period whereas in the reverse engine operation as illustrated in Fig. 4 the injection period takes place at a relatively longer time after the finish of the pump stroke. This means that in reverse engine operation the fuel pressure in the fuel supply system must be maintained for a longer period of time than in forward engine operation as shown in the diagram illustrating a single cylinder cycle. In a multi-cylinder engine a relatively less difference in the time interval will be present though it is possible to so time a multi-cylinder engine that no appreciable difference will be present. I find however, that such a variation does not materially alter the operating efficiency of the engine in which is employed a common rail variable pressure fuel supply system. It will be noted that the injection period in forward operation of the engine (herein illustrated as a single cylinder engine) opens a number of degrees ahead of top dead center piston position and closes a few degrees after top dead center piston position. If desired, I may commence injection as high as 25° before top dead center and close as low as 5° past top dead center piston position. In engines of this character it is usually preferable to provide an injection period of approximately 30° of crankshaft rotation, but obviously this period may be varied if so desired and the time of opening and closing may be also varied as found desirable. In engines of this character, means are generally provided for adjusting the injection period and this adjustment may be employed if so desired to vary the opening and closing of the injection period when the engine is reversed so as to obtain better efficiency in reverse than if the injection period had been left unchanged. Since the engine is operated a major portion of the time forwardly, the timing of the injection period is preferably arranged to favor forward engine operation. Preferably, the sleeve valve means is advanced with respect to the piston by setting the valve crank in advance of the power piston's crank.

It will be noticed by observing Figs. 5 and 6 that very little change in valve opening area takes place when the valve C is operated to reverse the direction of the intake and exhaust gases. These figures which diagrammatically illustrate the port area as plotted against crankshaft angle show very little variation and in practice I find that this variation is substantially negligible for all practical purposes.

It will be noted that the construction herein illustrated and described provides an engine that may be easily reversed in operation with a minimum of effort. No complicated mechanism is employed for changing the timing of the various operating accessories associated with said engine since in the particular type of engine with which I have incorporated my invention, I find that the reversing of the intake and exhaust takes

place with a negligible variation in the timing of other associated engine parts.

It will be apparent to those skilled in the art to which my invention pertains that various modifications and changes may be made therein without departing from the spirit of my invention or from the scope of the appended claim.

What I claim as my invention is:

10 In an engine of the fuel injection type having a crankshaft and a common rail variable pressure fuel supply system including a fuel pump operated by said crankshaft, a cylinder ported for intake and exhaust, valve means for controlling said ports, said valve means operatively connect-

ed with the crankshaft, a manifold structure having intake and exhaust gas conducting means, and valve means associated therewith for selectively connecting said cylinder ports with either of the manifold intake and exhaust gas conducting means whereby to permit forward and reverse operation of the engine, the relative positions of the elements of said fuel supply system with respect to the crankshaft remaining unchanged for forward and reverse engine opera- 10
